UNITED STATES PATENT OFFICE.

STEPHEN P. HART, OF BOSTON, MASSACHUSETTS.

BARREL-SYRINGE.

Specification of Letters Patent No. 25,409, dated September 13, 1859.

To all whom it may concern:

Be it known that I, STEPHEN P. HART, of Boston, in the county of Suffolk and State of Massachusetts, have invented an 5 Improvement in Enema-Syringes, of which the following is a full, clear, and exact description, reference being had to the accompanying drawing, making part of this specification, in which is represented a longitudinal section through one of my improved 10 syringes.

The well known syringe consisting of an elastic india rubber globe or egg shaped vessel with an induction and an eduction tube 15 or pipe, is liable to several objections, the chief of which arises from the liability of the syringes to get out of order and require repairs, and the failure of the globe after being some time in use to expand with sufficient 20 readiness after being compressed. To remedy these difficulties the india rubber globe has been replaced by a small metallic syringe, but this was found to be inconvenient as it required both hands to operate it.

25 My invention consists in the insertion of a spring within a metallic syringe so arranged as to raise the piston after it is depressed by hand and by which means it may be operated by one hand.

30 To enable others skilled in the art to understand my invention I will proceed to de-

scribe the manner in which I have carried it out.

A is the induction pipe, the entrance to which is commanded by a valve b.

35 C is the metallic barrel of the syringe from the base of which rises a rod D, which enters the piston rod F when the piston is depressed.

g is a coiled spring which surrounds the 40 rod D, and by which the piston is raised after being depressed, and when the handle H is released by the hand.

K, is the eduction pipe having a disk valve 45 e of india rubber to prevent the entrance of air when the piston is raised.

In operating this syringe, the barrel C' is held between the first and second fingers of the right hand, and the piston is depressed by pressure of the thumb upon the handle 50 H. This is repeated as many time as may be necessary, the piston being raised after each depression by the spring g.

55 What I claim as my invention and desire to secure by Letters Patent is—

The spring g as applied to the syringe operating in the manner substantially as set forth.

STEPHEN P. HART.
